BREAST LIFTER FOR COTTON GINS

John Blewett, Dallas, Tex., assignor to The Murray Company, Dallas, Tex., a corporation of Texas

Application August 30, 1935, Serial No. 38,545

9 Claims. (Cl. 19—55)

This invention relates to new and useful improvements in breast lifters for cotton gins.

In the ginning of cotton, it has been found that due to the fact that the cotton which is brought to the gin plant has a considerable amount of hulls, trash, sticks, stems, etc., it is necessary to dump the contents from the roll box of the gin several times daily. Otherwise, the seed in the roll box becomes so mixed with this extraneous matter that said seed is undesirable for planting purposes. Also by keeping the roll box clean of this extraneous matter, a better sample may be obtained when ginning hulky cotton.

To dump the contents of the roll box in the ordinary gin now in general use, it is necessary to first stop the gin and then lift the inner and outer fronts off the gin. The seed is then removed from the roll box with the hands. This not only is inconvenient to the gin operator, but it is obvious that to dump the contents of the roll boxes of a four- or five-stand battery of gins, considerable time is spent in removing and replacing the fronts. This results in a loss of ginning time, which causes expense to the gin operator.

One object of the invention is to provide a simple, manually operated means for dumping the contents of the roll box of a cotton gin, whereby said box may be readily cleaned of seed, trash, etc. at any desired time and without halting the driving mechanism of the gin.

An important object of the invention is to provide improved means for swinging the huller breast of a cotton gin away from the inner ginning breast, said means having automatic locking means for locking the huller breast to the inner breast when the former is in an inner or closed position, said means also serving to lock the huller breast in its outer or open position.

Another object of the invention is to provide an improved lifter for swinging the huller breast which carries the huller ribs outwardly from the inner breast to permit the escape of the contents of the roll box, together with means for aligning the two breasts when the huller breast is returned to its original closed position so that the huller ribs are positively aligned with the gin saws when said huller breast is returned, said aligning means being readily adjustable to compensate for slight variations in the position of the huller ribs in various gins.

A further object of the invention is to provide a series of levers and links which operate swinging cams, said cams being attached to the inner

ginning breast of a cotton gin and arranged to move the huller breast outwardly when swung, the levers and links being so arranged as to lock the cam in its extreme positions, whereby the huller breast is locked in its outer or open position, and is also locked to the inner breast when in its inner or closed position, whereby if desired, the huller and ginning breasts may be swung as a single unit.

Still another object of the invention is to provide an improved lifter for the huller breast of a cotton gin, which is so constructed as to be readily attached to an ordinary gin, and which, when attached, will not interfere with the normal operation of said gin.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a side elevation of a cotton gin, having a breast lifter, constructed in accordance with the invention attached thereto, and showing the huller breast in a closed or inner position,

Figure 2 is a view, similar to Figure 1, showing the huller breast swung outwardly to an open position,

Figure 3 is a perspective view of the breast lifter, with the gin being shown in outline to illustrate the relation of the various parts to each other,

Figure 4 is a diagrammatical, vertical, sectional view of the gin,

Figure 5 is a horizontal, cross-sectional view, taken on the line 5—5 of Figure 1,

Figure 6 is an isometric view of the keeper,

Figure 7 is a partial side elevation of a gin having a modified form of the invention attached thereto, and

Figure 8 is an isometric view of the upper end of the same.

In the drawings the numeral 10 designates a cotton gin which may be of the usual construction. The gin includes the ordinary supporting frame 11 and the usual row of gin saws 12 are mounted transversely between the ends of the frame on a transverse saw shaft 13 (Figure 4). The ginning ribs 13 which are carried by the pivoted inner ginning breast 14 are disposed between the saws in the usual way. The huller ribs 15 which extend transversely within the pivoted

huller breast 16 of the gin are located in alignment with the gin ribs, in the usual way when the huller breast is swung inwardly against the inner breast, as is clearly shown in Figure 1. The above parts are all of the usual construction in cotton gins, and are therefore subject to variation. It will be seen that the usual roll box A is formed above the ginning and huller ribs 13 and 15, and during the operation of the gin, the roll will be built up in the roll box. The seeds which are ginned in the usual way will, of course, escape between the gin ribs 13 and the huller ribs 15 in an ordinary manner.

It has been found that when ginning hilly cotton, or cotton which has trash, sticks and stems mixed therewith, that it is desirable to dump the contents of the roll box at intervals because the trash, sticks and other extraneous matter will accumulate in said roll box, whereby a poorer sample is obtained through ginning. There is no set time when this roll box should be emptied, as the condition of the cotton introduced into the gin will control. Sometimes it is found necessary to empty the contents of the roll box several times daily, whereas other times only a single emptying per day is found sufficient. In all cases, however, it is desirable that the roll box be emptied at some time.

For emptying the roll box, it will be seen that if the huller breast 16 is swung on its pivot 17 which is near the upper end of said huller breast, the lower end of said huller breast is swung outwardly away from the inner ginning breast 14. When said huller breast swings away from the inner breast, it will be seen by observing Figure 4, that the huller ribs are swung from between the ginning saws 12 and away from the gin ribs 13. Thus the contents of the roll box A may escape through this space which when the huller breast is in its inner or closed position is the seed outlet.

For quickly and easily swinging the huller breast 16 on its pivot 17, a pair of cam members 18 are provided. The cam members are mounted one on the outer side of each end wall of the cotton gin, as clearly shown in Figure 3, and since the structure of the cam members and their operating link is exactly the same, it is believed that a description of one will suffice. Each cam member 18 is pivoted on the outer end of a transverse shaft 18' which extends between the end wall of the gin. It is noted that the cam is located on the outside of said wall and is disposed nearer the lower end of the inner breast 14. As clearly shown in Figure 1 the cam member is preferably cast, and is provided with a hook member 19 at the upper end of the cam face 20. The lower end of the cam face 20 is provided with a recess 21. When the huller breast 16 is in its inner or closed position, the location of the cam member 18 is such that the hook member 19 engages over a pin 22 which extends outwardly from the side of the huller breast. The engagement of the hook 19 over said pin serves to lock the huller breast 16 to the inner ginning breast 14, whereby the two breasts may be swung as a single unit on the pivot of the inner breast 14.

Extending upwardly from the pivot point of the cam members 18 is an arm 20' which is preferably cast integral with the cam member. For swinging the cam member so that its cam face 20 will ride against the pin 22, an elongated adjustable connecting link 23 has its lower end pivoted to the upper end of the arm 20'. The upper end of the link is curved rearwardly of the gin and is pivoted to a curved hand lever 24, as

is clearly shown in Figure 3. The curved hand lever has its lower end pivotally mounted on the outer end of a transverse shaft 25 which extends between the end walls of the gin and is suitably mounted in bracket 26. Due to the upper curved end of the link 23 being pivoted to the curved lever 24 it will be seen that when the huller breast 16 is in a closed or inner position, with the hook 19 of the cam member 18 engaging over the pin 22, that the pivotal connection 23' of said link with said lever is at a point beyond the vertical axis of the transverse shaft 25. Therefore the pivotal connection 23' is beyond the center of the pivot 25 of the manual operating lever 24. Since it is past center, it will be seen that such disposition will serve to lock the lever, link 23 and cam member 18 in this position. Therefore, when the huller breast 16 has been moved to its inner position in engagement with the front face of the inner breast 14, it is impossible for said huller breast to be swung outwardly until such time as the lever 24 is swung downwardly through a manual operation because the various parts are locked in position. This eliminates any danger of the hook 19 disengaging the pin 22 to permit a separation of the two breasts until such time as the operator may so desire.

When it is desired to swing the huller breast 16 outwardly to open the space between the huller ribs 15 and the ginning ribs 13 to permit an escape of the contents from the roll box A, it will be seen that a downward pull on the lever 24 will, of course, cause the link 23 to move downwardly also. The downward movement of the elongated link 23 will cause the cam member 18 to be swung on its pivot shaft 18'. As said cam member is swung the cam face 20 of said cam member will ride against the pin 22 which extends outwardly from the side of the huller breast 16. The disposition and curve of the cam face is such that as the cam member 18 is swung through the movement of the hand lever 24 and link 23, said cam face will force the huller breast 16 outwardly away from the inner ginning breast 14. Continued movement of the lever 24 will swing the cam member 18 to the position shown in Figure 2, whereby the pin 22 is engaged in the recess 21 at the lower end of the cam face 20 of said member 18. When said recess has been engaged by the pin 22 the pivotal connection 22' between the arm 20' and the lower end of the link 23 has moved to a point below the pivot 18' of the cam member. In other words, the point 22' is below the transverse shaft 18' in a horizontal plane. Since it is below such point, it will be seen that it has been swung past center which will serve to lock the parts in this position. Therefore, it will be seen that there is no danger of the huller breast 16 swinging into its closed position accidentally, because it will take a certain pull on the lever 24 which has moved to the position shown in Figure 2 to cause the link 23 to travel upwardly to again return the cam member 18 to its original position.

From the above it will be seen that the cam member, link 23 and manual operated lever 24 provide a simple means which will swing the huller breast 16 either to its outer or open position or will return to its inner or closed position. The actuation of the cam member 18 is accomplished quickly and easily by merely grasping the handle 24' of the lever 24. There is no disassembling of any parts of the gin front necessary to dump the contents of the roll box A therefrom.

It has been found that a single manually operated lever 24 is sufficient, and therefore only one of the cam members 18 is provided with the hand lever 24. The other cam member 18 has the upper end of its link 23 pivoted to a rocker arm 27, as is clearly shown in Figure 3. The rocker arm is fixed to the transverse shaft 25 and since the lever 24 is also fastened on said shaft, it will be obvious that a swinging of the lever 24 will rotate said shaft, which in turn will swing the rocker arm 27 to actuate the other cam member 18 simultaneously with the actuation of the first cam member 18. It is noted that providing the two cam members, one on each side 15 of the huller breast 16 that a more rigid and even movement of the huller breast 16 may be had. If only a single member were provided there would be a tendency for the huller breast to twist transversely when said member was 20 operated.

It will be seen that when the huller breast 16 is swung outwardly, through the actuation of the cam members 18, that the huller ribs 15 will be moved from between the saws 12 within 25 the gin. Therefore, when the huller breast 16 is returned to its original or closed position it is essential that the huller ribs 15 be again aligned exactly with the ginning ribs 13 between the saws 12. If the ribs are not exactly in alignment, the 30 efficiency of the operation of the gin will be decreased. To provide for this alignment of the huller ribs 15 exactly with the ginning ribs 13, the outer side of each end of the huller breast 16 is provided with a keeper 30. The keeper is 35 clearly shown in Figures 5 and 6 and is preferably angular in cross-section having one leg 30' extending outwardly from the end wall of the huller breast. This leg 30' is provided with a suitable opening 31 near its outer end. The other 40 leg of the keeper is fastened to the end wall of the huller breast by a suitable cap screw 32. Suitably secured in each end wall of the inner breast 14 at the lower end thereof is a dowel pin 33 which extends forwardly from said breast. 45 The dowel pin 33 is so located as to engage the opening 31 in the leg 30' of the keeper 30 when the huller breast 16 is in a closed or inner position. The edges of the opening 31 are preferably beveled, while the dowel pin has its end rounded, 50 whereby when the breast 16 is returned to an inner position after having been swung outwardly, the pin 33 will be guided into the opening 31. When the pin is centered within said opening the proper alignment of the huller breast 16 with the 55 inner breast 14 is had, whereby the alignment of the huller ribs 15 with the ginning ribs 13 is correct.

Due to the fact that in different gins, there 60 might be a variation in the positioning of the huller ribs 15 therein, it is sometimes necessary to vary the alignment of the huller breast 16 with the inner breast 14. In other words it might be necessary that the huller breast, when in its inner position, is one-eighth of an inch out of 65 alignment with the inner breast 14. This is necessary to properly align the huller ribs between the ginning saws 12. In such case shims 34 may be inserted between the rear side of the angular keeper 30 and the end wall of the huller 70 breast 16. It is obvious that by employing more or less of the shims, that the opening 31 in the outwardly extending leg 30' of the keeper may be moved closer or further away from the end wall of the huller breast 16. If it is positioned further 75 away it will be obvious that when the dowels en-

ter said opening the end wall of the huller breast 16 will be moved a little further inwardly with relation to the end wall of the inner breast 14, than it would be if the opening 31 were positioned closer to the wall of said huller breast. 5 Through the use of the shims and the particular construction of the keeper 30, it is possible to exactly align the huller breast 16 in its proper position so that the huller ribs 15 will be properly positioned between the ginning saws 12. It is 10 noted that a keeper is formed on each end wall of the huller breast at the extreme lower end thereof, while the complementary dowel pin for each keeper is mounted in the end wall of the inner breast 14 at its lower end. 15

From the above it will be seen that a simple and efficient means is provided for readily swinging the huller breast 16 outwardly from the inner ginning breast 14, whereby the contents of the roll box A may easily escape through the seed 20 outlet between the huller ribs 15 and the ginning ribs 13. The operator merely has to grasp the handle 24' of the lever 24 and swing the said lever to the position shown in Figure 2. This will swing the huller breast 16 outwardly as shown 25 in this figure and due to the swinging of the pivotal connection 22' of the lower end of the link 23 with the arm 20' past the horizontal center of the transverse shaft 18' on which the cam members 18 are pivoted, the parts are locked 30 in this position. There is no danger of the huller breast 16 swinging back to its inner or closed position accidentally, and therefore said breast cannot be returned to its original position until such time as the operator again grasps the handle 35 24' and swings the lever 24 to its original position. When it is so swung the weight of the lower end of the huller breast 16 will, of course, cause the same to swing inwardly to the breast 14 and the hook 19 of the cam member 18 will 40 engage over the outwardly extending pin 22 on said huller breast. Since the pivotal connection 25' between the upper end of the links 23 with the lever 24 and rocker arm 27 is swung past the vertical center of the transverse shaft 25, it will 45 be seen that the parts are locked in position when the huller breast 16 has been returned to its closed position. While swinging to an inner position, the huller breast 16 is guided into its proper alignment with the inner breast 14 by the 50 dowel pin 33 and keeper 30, whereby the huller ribs 15 are properly aligned between the ginning saws 12. It is obvious that no adjustments are necessary in the connection of the links 23 with their respective ports. It might be necessary in 55 applying the lifting means to various sized gins to lengthen or shorten the links 23 and for this purpose the adjustable screw bolts and lock nuts 35 are provided. This adjustment may be accomplished quickly and easily. The adjustment 60 of the keeper 30 by the removing or inserting of the shims 34 is also readily accomplished by merely removing the cap screws 32 and making such removal or insertion.

In Figures 7 and 8, I have shown another way 65 of locking the parts in their respective positions when the huller breast 16 is swung to its inner or closed position. In this form the curve in the upper end of the links 23 is eliminated and said link is pivotally connected at a point 35' to the 70 lever 24. This pivotal connection is at a point which is not beyond the vertical center of the transverse shaft 25 and therefore no locking action is had between the pivot points. However, for holding the lever in this position a flat spring 75

36 is suitably secured to the end wall of the inner breast 14. The outer end of this spring is bent upon itself to form a lug 37 which engages the edge of the lever 24, as is clearly shown in 5 Figure 8. So long as the spring 36 is in its normal position it will be obvious that it will prevent the downward swinging of the lever 24 to operate the cam members 18. When it is desired to swing said lever 24, it is only necessary 10 to manually depress the spring whereby the lever 24 will clear said spring on its downward swing. After the huller breast has been swung outwardly it will be obvious that the position of the hand lever will be as shown in Figure 2 and will not be 15 opposite the flat spring 36. Thus the spring 36 has returned to its normal or outer position. Therefore when the huller breast 16 is again 20 swung inwardly through the upward swinging of the handle, it will be obvious that the handle during its upward swing will engage the outer 25 face of the spring 36 to depress the same and permit the passage of the lever thereby. As soon as the lever has swung to a point beyond the outer end of the spring 36, said spring will 30 immediately spring to its normal position whereby downward movement of the handle is again arrested, until such time as the spring 36 is again manually depressed. It is pointed out that 35 various ways of locking the lever, links, and cam 30 in their respective positions when the huller breast 16 is either swung inwardly or outwardly may be devised, and the invention is not to be limited to any particular type of locking means.

The simplicity of the lifting means permits 35 the huller breast 16 to be swung outwardly to empty the contents of the roll box A in a minimum amount of time. The only time necessary is such time as it will take to swing the hand lever 24 from one position to another. The parts 40 may be returned to their original position just as easily and quickly. There is no necessity of removing any of the front walls of the cotton gin and further the escape of the contents of the roll box is accomplished automatically by gravity. 45 There is no need for the trash or seeds in the roll box being removed by hand, as is the usual practice. It is further noted that the swinging of the huller breast 16 may be accomplished without stopping the operating mechanism of the 50 gin. In other words the saws 12 may continue to operate during the swinging of said breast.

What I claim and desire to secure by Letters Patent is:

1. A breast lifting device including, means pivoted on the inner breast of a cotton gin, means on the hinged outer breast of said gin arranged to be engaged by the pivoted means when the latter is swung to move the outer breast outwardly away from the inner breast to an open position, operable means pivotally connected to said pivoted means for swinging said pivoted means to effect a dumping of the roll, means carried by said pivoted means for locking the outer breast in its open or closed position, and means for aligning the outer breast with the inner breast whereby after the outer breast has been swung and is returned to its closed position, the huller ribs of the gin which are carried by said outer breast are aligned with the ginning saws of said cotton gin. 65
2. A breast lifting device including, means pivoted on the inner breast of a cotton gin, means on the hinged outer breast of said gin arranged to be engaged by the pivoted means when the latter is swung to move the outer breast outwardly away from the inner breast to an open 70
- 75

position, manually operated means pivotally connected to said pivoted means for swinging the pivoted means to effect a dumping of the roll, means carried by said pivoted means for locking the outer breast in an open or closed position, and means for aligning the outer breast with the inner breast whereby after the outer breast has been swung and is returned to its closed position, the huller ribs of the gin which are carried by said outer breast are aligned with the ginning saws of 10 said cotton gin. 15

3. A breast lifting device including, cam members pivoted on each end wall of the inner breast of a cotton gin, an outwardly extending pin on each end of the outer pivoted breast of said gin 15 and arranged to be engaged by the cam members when the latter are swung, whereby the outer breast is swung outwardly to an open position when said cam members are swung, operating means pivotally connected to said cam for swing- 20 ing said members, and means carried by said cam for locking the outer breast in either its open or closed position.

4. A breast lifting device including, cam members pivoted on each end wall of the inner breast 25 of a cotton gin, an outwardly extending pin on each end of the outer pivoted breast of said gin and arranged to be engaged by the cam members when the latter are swung, whereby the outer breast is swung outwardly to an open position 30 when said cam members are swung, operating means pivotally connected to said cam for swing- ing said members, means carried by said cam for locking the outer breast in either its open or closed position, and means for aligning the outer breast 35 with the inner breast when the former is returned to a closed position after having been swung through the operation of the cam member, whereby the huller ribs of the gin which are carried by said outer breast are aligned with the ginning 40 saws. 45

5. A breast lifting device including, a pair of cam members which are pivoted one on each outer side wall of the inner breast of a cotton gin, outwardly extending pins on the outer breast 45 of said gin and arranged to be engaged by the pivoted cam members when the members are swung, whereby the outer breast is swung either inwardly or outwardly to its open or closed position, means on the cam member for receiving the pins said means being at the ends of the cam member to retain the outer breast in its extreme 50 positions, a manually operated lever pivoted near the upper end of the inner breast, and means for connecting said lever with the cam members 55 whereby swinging of the lever will swing said members to control the movement of the outer breast. 60

6. A breast lifting device including, a pair of cam members which are pivoted one on each outer side wall of the inner breast of a cotton gin, outwardly extending pins on the outer breast of said gin and arranged to be engaged by the pivoted cam members when the members are swung, whereby the outer breast is swung either inwardly 65 or outwardly to its open or closed position, means on the cam member for receiving the pins said means being at the ends of the cam member to retain the outer breast in its extreme positions, a manually operated lever pivoted near the upper 70 end of the inner breast, and adjustable means for connecting said lever with the cam members whereby swinging of the lever will swing said members to control the movement of the outer breast, the connection of the adjustable means 75

5 with the cam members and the lever being such that when the outer breast is in either its completely open or completely closed position, the cam members are located in such position, whereby by danger of the outer breast accidentally moving from such position is eliminated.

7. In a breast lifting device, the combination with the inner breast and the outer breast of a cotton lint removing machine, of a member pivoted on the inner breast and having a locking element, an abutment on the outer breast engaged by the locking element of the member for normally locking the outer breast in its inward position, means on the pivoted member for engaging the abutment to swing the outer breast outwardly when said member is swung, and means for swinging the pivoted member to unlock the element from the abutment and to swing the outer breast outwardly.
- 10 8. In a breast lifting device, the combination with the inner breast and the outer breast of a cotton lint removing machine, of a member pivoted on the inner breast and having a locking element, an abutment on the outer breast engaged 15 by the locking element of the member for nor-

20 mally locking the outer breast in its inward position, means on the pivoted member for engaging the abutment to swing the outer breast outwardly when said member is swung, means for swinging the pivoted member to unlock the element from the abutment and to swing the outer breast outwardly, and means on the pivoted member for engaging the abutment to hold the outer breast in its outer position.

9. In a breast lifting device, the combination 10 with the inner breast and the outer breast of a cotton lint removing machine, of a member pivoted on the inner breast and having a locking element, an abutment on the outer breast engaged by the locking element of the member for normally locking the outer breast in its inward position, means on the pivoted member for engaging the abutment to swing the outer breast outwardly when said member is swung, means for swinging the pivoted member to unlock the element from 15 the abutment and to swing the outer breast outwardly, and means to latch the swinging means whereby the pivoted member is latched.

JOHN BLEWETT. 25
